UNITED STATES PATENT OFFICE.

BUTLER AMES, OF LOWELL, MASSACHUSETTS.

MEANS FOR SUPPORTING SPARK-COIL CASES.

1,030,858.

Specification of Letters Patent.

Patented July 2, 1912.

Application filed September 5, 1911. Serial No. 647,488.

To all whom it may concern:

Be it known that I, BUTLER AMES, a citizen of the United States, residing at Lowell, in the county of Middlesex and State of Massachusetts, have invented certain new and useful Improvements in Means for Supporting Spark-Coil Cases, of which the following is a specification, reference being had therein to the accompanying drawing.

10 The principal object of my invention is to economize space occupied by spark-coils back of the dash-board of an automobile, and I attain this object by so designing the spark-coil case and the dash-board that the 15 case is in front of the rear of the dash-board, while the vibrating mechanism of the spark-coil is accessible at the back of the dash-board.

In the drawings illustrating the principle 20 of my invention and the best mode now known to me of embodying the same in operative structure, Figure 1 is a perspective view showing two spark-coil cases mounted in the dash-board of an automobile; the 25 cover of one case being removed, and the dash-board broken away to show how one or more cases and board may be combined. Fig. 2 is an elevation in section, the spark-coil having been removed from its case. 30 Fig. 3 is an elevation of an internally and externally screw-threaded metallic ring to receive the top portion of the case, and to be screwed into a hole in the dash-board; while Fig. 4 is a similar view of a cap to close the 35 screw-threaded end portion of the ring, shown in Fig. 3.

A spark-coil case 1, preferably of wood, and cylindrical in shape, has its open end portion provided with external screw 40 threads 2, Fig. 2, and is adapted to engage corresponding screw threads 3 therefor in a suitable hole cut through a suitable support, say a dash-board 4 of an automobile. These threads may be formed in a metallic 45 ring 5, Figs. 1, 2 and 3, having a flange 6, and internal and external screw threads formed thereon, as by stamping. The width of this ring is such that when the ring is screwed into the hole through the dash-board, and the flange 6, Fig. 2, is flush with the front of the board, where it is secured as by screws 7, the free end portion of the ring protrudes through the rear of the dash-

board, and is adapted to receive thereon a metallic threaded cap 8, Figs. 2 and 4, to close the open end of the ring. The cap has an outwardly extending flange 9 which serves to engage the dash-board closely and serve as a finish. Into the front opening of the ring 5 may be screwed the threaded portion of the coil case, as clearly appears in Figs. 1 and 2.

The case has the usual binding posts which may be connected up in any of the numerous ways commonly employed. It 65 being preferably of wood, it is desirable to treat the case chemically for the purpose of making it waterproof, and preventing it from being subject to undue swelling and shrinking.

Figs. 1 and 2 show clearly the merits of the invention; how little space at the rear of the board is taken up by the cap of the case, and how accessible becomes the vibrating mechanism 10 of the coil; and further, how 75 the greater part of the coil and its case are forward of the dash-board, and within, say, the space inclosed by the hood over the engine.

It is to be understood that, while this 80 method of mounting one or more spark coil cases, is of great utility in connection with the dash-board of an automobile, my invention may be applied to any other suitable environment, and may be embodied in many 85 formally different structures.

Desiring to protect my invention in the broadest manner legally possible, what I claim is:

1. A support having a screw-threaded 90 hole therethrough; a spark coil case, having a correspondingly threaded top portion to engage said screw-threaded hole; and means to cover said top portion.

2. A dash-board of an automobile, having 95 a hole therethrough; a metal ring mounted in and extending out of said hole, and having internal screw-threads therein; means for securing said ring in said hole; a spark coil case having a hollow cylindrical portion provided with screw-threads corresponding to those in said ring, and adapted to engage said latter threads; and a cap or cover for said case.

3. A dash-board of an automobile having 105 a hole therethrough; a metal ring mounted

in and extending through said hole, and having internal screw-threads thereon; means for securing said ring in said hole; a spark coil case having a hollow cylindrical portion provided with screw-threads corresponding to those in said ring, and adapted

threads to engage said screw-threads of said ring that protrude through said dash-board. 10
In testimony whereof I affix my signature in presence of two witnesses.

BUTLER AMES.
